UNITED STATES PATENT OFFICE

WALTER B. WEBER, OF MERWOOD PARK, PENNSYLVANIA

DESIGN FOR AN OFFICE PARTITION

Application filed January 19, 1932. Serial No. 42,547. Term of patent 3½ years.

To all whom it may concern:

Be it known that I, WALTER B. WEBER, a citizen of the United States of America, residing at Merwood Park, in the county of Delaware and State of Pennsylvania, have invented a new, original, and ornamental Design for Office Partitions, of which the following is a specification, reference being had to the accompanying drawings, forming part thereof.

Of the drawings:

Fig. I represents a front elevation of an office partition showing my new design; and, Fig. II represents an enlarged perspective view of a fragmentary portion of the same, showing a vertical section taken as indicated by the lines II—II of Fig. I.

I claim:

The ornamental design for an office partition, as shown and described.

WALTER B. WEBER.
